(57) **CLAIM**

The ornamental design for a rail for a shelving system, as shown and described.

DESCRIPTION

FIG. 1 is a perspective view of a first embodiment of a rail for a shelving system showing our new design;

FIG. 2 is an enlarged front end view of the rail of FIG. 1, the back end view being a mirror image thereof;

FIG. 3 is a right side view of the rail of FIG. 1, the left side view being a mirror image thereof;

FIG. 4 is an enlarged top view of the rail of FIG. 1;

FIG. 5 is an enlarged bottom view of the rail of FIG. 1;

FIG. 6 is a perspective view of a second embodiment of a rail for a shelving system;

FIG. 7 is an enlarged front end view of the rail of FIG. 6, the back end view being a mirror image thereof;

FIG. 8 is a right side view of the rail of FIG. 6, the left side view being a mirror image thereof;

FIG. 9 is an enlarged top view of the rail of FIG. 6; and,

FIG. 10 is an enlarged bottom view of the rail of FIG. 6.

The rail is shown broken-away in the views to indicate unclaimed length.
